UNITED STATES PATENT OFFICE.

SIMON LAKE, OF MILFORD, CONNECTICUT

ROOF OR THE LIKE STRUCTURE.

Original application filed August 20, 1924, Serial No 733,208, now Patent No. 1,562,706, granted November 24, 1925. Divided and this application filed October 27, 1925. Serial No. 65,150.

This case is a division of my application, Serial No. 733,208, filed August 20, 1924, now Patent No. 1,562,706, granted November 24, 1925.

5 The object of this invention is to provide a roof or the like structure of concrete or other suitable plastic material, having applied thereto, and preferably imbedded therein, surface finishing members of such a 10 nature as to form an exterior surface of a permanent water-proof character.

The invention consists in a roof or the like structure formed preferably of preformed slabs of concrete or other plastic material, 15 having incorporated therewith slates, tiles or other surface finish members, forming an integral part of the structure and providing upon the outer surface thereof a finish substantially the same in appearance as that of 20 the ordinary slate or tile roof or the like, but having an advantage thereover in that the slates or tiles are permanently applied to the slabs forming the structure and are so supported thereby and affixed thereto as 25 to greatly enhance their weather-proofing qualities and durability, and avoid breakage, as I will proceed now to explain and finally claim.

In the accompanying drawings illustrating the invention, in the several figures of 30 which like parts are similarly designated, Figure 1 is a fragmentary perspective view of a portion of a roof constructed in accordance with my invention. Fig. 2 is a fragmentary sectional detail upon a larger scale, 35 taken on the line 2—2 of Fig. 3, and showing the arrangement of the surface finish members or slates or tiles upon the structure. Fig. 3 is a section taken on the line 3—3 40 of Fig. 2. Fig. 4 is a fragmentary perspective view of a pallet suitable for the casting of slabs embodying my invention. Fig. 5 is a transverse vertical section of a 45 finished slab upon the pallet. Fig. 6 is a section taken on line 6—6 of Fig. 5.

My invention is adapted particularly for use in combination with preformed roof or wall slabs made in accordance with the invention of my application hereinbefore mentioned, 50 but it is obvious that its usefulness is not limited thereto, and that it may be used in connection with any roof or the like structure, formed of concrete or other plastic material, which lends itself to the features

of the method of manufacture hereinafter pointed out.

As shown in the drawings, I imbed in the plastic of the roof slab *a* or the like, during the process of its formation, a plurality of slates or tiles *1* forming the outer or surface 60 finish of the roof or the like, and arranged in staggered relation so as to break joints, as is customary in roofs of this type, whereby, in appearance, the roof is substantially the same as a slate or tile roof constructed 65 in accordance with ordinary practice.

Beneath the adjacent edges *2* of the slates or tiles, and spaced therefrom so as to be completely imbedded in the plastic of the structure, I provide breaker strips *3*, of tile, 70 slate, glass, copper, or other suitable material having a coefficient of expansion substantially the same as that of the concrete or other plastic. These breaker strips *3* seal the joints between the slates or tiles *1*, and, 75 as will be seen, particularly by reference to Figs. 1, 3, 4 and 5, the upper ends *4* of the slates or tiles underlie the lower ends *5* of the slates or tiles arranged above them, thus providing the customary overlapping 80 at the longitudinal joints of the slates or tiles.

The slates or tiles may be incorporated in a preformed roof slab of the type described in my patent above mentioned, which, when 85 finished, is applied to a building, by arranging them, face down, upon a pallet *b*, (see Figs. 4, 5 and 6) provided with surface members *6* of such conformation as to align them in courses and at the desired angle or cant 90 to provide for the customary lap, then positioning a suitable mold box *7* upon the pallet to define the shape of the slab, then pouring a thin layer of concrete, having preferably incorporated with it a water-proofing 95 material, upon the exposed surfaces of the slates or tiles. Before this layer of concrete has set the breaker strips are positioned in it in proper relation to the edges *2* of the slates or tiles, and thereafter the completing of the 100 formation of the slab is carried out as described in my Patent No. 1,562,707, dated November 24, 1925.

In this manner it will be seen that I produce a preformed roof or the like slab which, 105 when removed from the pallet and turned over, presents an outer finish surface composed of slates or tiles arranged in the cus-

tomary, approved manner and in appearance substantially the same as the ordinary slate or tile roof, but having marked advantages thereover.

5 Inasmuch as the slates or tiles are incorporated in the roof or the like structure while the material thereof is plastic, a bond between them and the structure itself is formed of such a tenacious nature that separation of the slates or tiles from the structure and derangement thereof upon the same is practically impossible. Moreover, due to the unbroken contact of the plastic of the structure with the whole under surface of 15 each of the slates or tiles, a support for each of the tiles is provided which makes remote the possibility of the breaking of same by impact of bodies or by blows struck upon their exposed surfaces.

20 Furthermore, the roof will be fireproof, and all of the materials used in its formation having substantially the same coefficient of expansion there will be no tendency to form cracks or fractures under the influence 25 of heat and cold.

A roof or the like constructed in accordance with my invention has qualities of permanence not heretofore attained in structures of this character, and has advantages 30 over ordinary concrete, slate, tile and the like roofs in that it combines with the permanence of the concrete roof, the water and weatherproof features of the slate, tile or the like roof. It moreover has the advantage 35 over the latter in that the slates or tiles are permanently affixed and imbedded in the concrete.

Various changes are contemplated as 40 within the principle of the invention and the scope of the following claims.

What I claim is:—

3. A preformed roof slab or the like structure of plastic material, including an exterior surface composed of a plurality of sur-

45 face finish members arranged in courses one above the other and with the edges of adjacent courses overlapping, and breaker strips arranged beneath the adjacent edges 50 of the members of each course, said surface finish members and said breaker strips being permanently bonded with the material of the structure.

4. A preformed roof slab or the like structure of plastic material, including an exterior surface composed of a plurality of surface finish members arranged in courses one above the other and with the edges of adjacent courses overlapping, and breaker strips arranged beneath the adjacent edges of the members of each course, said surface finish 55 members and said breaker strips being permanently bonded with the material of the structure and said material extending between and separating all of said surface finish members from each other.

60 1. A preformed roof slab or the like structure of plastic material, including an exterior surface composed of a plurality of surface finish members arranged in courses one above another and with the edges of adjacent courses overlapping, said surface finish members being permanently bonded with the material of the structure.

65 2. A preformed roof slab or the like structure of plastic material, including an exterior surface composed of a plurality of surface finish members arranged in courses one above the other and with the edges of adjacent courses overlapping, said surface finish 70 members being permanently bonded with the material of the structure and said material extending between and separating all of said surface finish members from each other.

75 3. In testimony whereof I have hereunto set my hand this 26th day of October, A. D. 1925.

SIMON LAKE.
